UNITED STATES PATENT OFFICE.

THOMAS DANIEL KELLY, OF ESSEX, ENGLAND.

INTERNAL-COMBUSTION ENGINE.

No. 922,911.

Specification of Letters Patent. Patented May 25, 1909.

Application filed November 8, 1907. Serial No. 401,305.

To all whom it may concern:

Be it known that I, THOMAS DANIEL KELLY, a subject of the King of Great Britain, residing at 20 Cliff avenue, Westcliff-on-Sea, Essex, England, engineer, have invented certain new and useful Improvements in Internal-Combustion Engines, of which the following is a specification.

The present invention relates to improvements in internal combustion engines of the two cycle type and wherein a set of three cylinders or a multiple thereof is employed, the cranks of the engine serving to time the operations of the pistons so that each cylinder will operate one-third of a revolution in advance of the next cylinder so that the engine pistons and pumps will so operate that at each revolution of the crank shaft, power is imparted thereto from any one piston during one-third of the revolution of the shaft, the exhaust gases are discharged and new charges are being admitted to the respective cylinder during another third of the revolution of the shaft, and compression is taking place during another third of the revolution of the crank shaft.

Another object of the invention is to provide an improved engine of this character wherein the main exhaust port of each cylinder opens preliminarily to the opening of an auxiliary exhaust port, the gases exhausted from the main exhaust port being conducted to a muffler while the auxiliary port may discharge into the atmosphere, and while these auxiliary ports of the cylinder are open to the atmosphere, the incoming charges of the explosive mixture cause the dead gases to be discharged therethrough, back pressure being thereby eliminated.

A further object of the invention is to provide means for introducing mixed air and water into the cylinders while the exhaust ports thereof are open whereby the exhaust gases are discharged and the working parts of the engine are cooled.

The annexed drawings illustrate how I carry my invention into effect.

Figure 1. is a sectional elevation of three cylinders with their pistons, connecting pipes, valves and crank shaft. Fig. 2. is an end elevation of the cranks and shaft showing their positions when the pistons are as at Fig. 1. Fig. 3. is a diagram of the working piston's stroke. Fig. 4. is a diagram of the pump stroke, A to B indicating suction, B to C compression, and C to A pumping charge

into working cylinder. Fig. 5. is a sectional elevation (enlarged) of the air and water scavenging valves and the box.

The pistons 1, 2 and 3 with their pumps 4, 5 and 6 are arranged in cylinders 7, 8 and 9, in a well-known manner, each piston being connected by a rod to a crank 10, 11 and 12, of the crank shaft 13. These cranks are positioned at 120 degrees with each other or in other words at equal distances around the circumferential travel of the crank shaft 13. In this position, the piston 1 is situated at the top of the stroke, piston 2 two thirds of the down stroke and piston 3 one third of the upstroke.

At the head of each cylinder or at other suitable part is situated an inlet valve 14, 15, 16, these opening from the cylinder each into a box 17, 18 or 19, each of which boxes is provided with an air inlet valve 20, 21, 22, and also a water valve controlled by needles 27, 28, and 29, the water pipe 30, 31, 32 leading to the seatings of the valves 20, 21, 22.

Each box 17, 18, 19 has a pipe 33, 34, 35, 36 leading to the cylinder 36 of the pump piston 5, the pipe 34 leading to the cylinder 37 of the pump piston 6, and the pipe 35 leading to the cylinder 38 of the pump piston 4.

39, 40 and 41 are the combustion mixture inlet valves.

A set of pipes 42, 43 and 44 extend from the respective engine cylinders and lead to one or more mufflers of any suitable construction.

45, 46 and 47 are auxiliary exhaust ports leading to the atmosphere.

In the position shown, the piston 1 has just received the explosion, and is on the downward stroke. Piston 2 has been moved down by the expansive force of the explosion in its cylinder, and is just reaching the main exhaust 43. Piston 3 is one third of its travel on the up stroke, and is commencing to compress the combustible mixture forced into the cylinder 9 by the previous upstroke of the pump 4. On the downstroke of the pump 5 air has been drawn into the pipe 33 and cylinder 36, through the valve 20, and at the same time water has been drawn in with the air from the supply pipe 30, also a charge of gas and air is drawn into the cylinder 36 by the pump 5 through the valve 40, and this supply being closer than the air and water supply is drawn in next to the piston 5, so that on the ejection, the water and air drawn into the

pipes can act as a scavenging charge to the cylinder 7 before entry of the combustible charge. The pump 6 has drawn in the charge of combustible mixture through the valve 41, 5 and also the air and water through the valve 21 and pipe 31 respectively, but in the position shown the pump is just about to eject the water and air through the pipe 34 into the cylinder 8, which it does immediately 10 after the main exhaust 43 is open, so that the pressure is released in the cylinder 8 to allow of the pressure in the cylinder 37 overcoming the valve 15. The piston 1 is now on its down stroke, and so soon as it reaches the 15 main exhaust 42, the expansive products of combustion exhaust themselves through the exhaust 42 and pass away. As the exploded gases pass away, the scavenging charge of air and water from the cylinder 36 and its 20 pipe 33 pass into the cylinder to clear same of the remaining gases, followed by the combustible charge from the cylinder 36. Just as the piston 1 passes the exhaust 42, the auxiliary exhaust 45 is opened, so the 25 remaining gases may be forced out without being checked by the exhaust gases in the silencer, thus creating a clean cylinder each time. During the downward movement of this piston, the pump has drawn in a charge 30 of gas and air and also water and air as previously mentioned with regard to pump 5. The piston 1 has now reached the end of the downward portion of the stroke, and commenced the upward portion of the stroke to 35 compress the combustible charge in its cylinder 7, the pump 4 forcing the charge in its cylinder 38 and the air and gas in the pipe 35, through the pipe 35 into the cylinder 9, the action of the different pistons and pumps be- 40 ing in sequence.

What I do claim, and desire to secure by Letters Patent is:

1. An internal combustion engine including a cylinder having a piston to operate therein and a suitable crank shaft, the cylinder being provided with a main exhaust port which is opened when the piston approaches the end of its power stroke and also an auxiliary exhaust port arranged to be opened 45 during the further movement of the piston toward the end of said stroke, and means for introducing a mixture of air and water into the said cylinder after the main and auxiliary ports thereof have been opened to expel the 50 products of combustion therethrough.

2. An internal combustion engine including a plurality of cylinders having pistons to operate therein and a suitable crank shaft, each cylinder having a main exhaust port 55 which is opened when the respective piston approaches the end of its power stroke, and also an auxiliary exhaust port arranged to be opened during the further movement of its respective piston toward the end of its power 60 stroke, a pump operable by each piston, and

means for introducing a mixture of air and water from the several pumps into the cylinders with which the said pumps communicate after the main and auxiliary exhaust ports thereof have been opened to expel the 70 products of combustion therethrough.

3. An internal combustion engine including a cylinder having a piston to operate therein, said cylinder being provided with an exhaust port through which the consumed 75 gases may be discharged, a pump, a pipe communicating with the pump and with said cylinder, means for admitting air and water to said pipe during the suction stroke of said pump, a carbureter for admitting gas directly 80 to said pump and during its suction stroke and means for operating said pump on its power stroke to first discharge the mixed air and water into said cylinder after the exhaust port thereof has opened and to subsequently 85 force the explosive gas into the engine cylinder.

4. An internal combustion engine including a cylinder provided with a piston, said cylinder having an exhaust port, a pump, a 90 pipe leading to the pump and communicating with the cylinder, and a valve communicating with sources of air and water and serving to admit said fluids into said pipe during the suction stroke of said pump, and 95 means for operating the pump on its compression stroke while the said exhaust port is open to introduce the mixed air and water into said cylinder to exhaust the consumed gases therefrom through said exhaust port. 100

5. An internal combustion engine including a cylinder having a piston to operate therein and a suitable crank shaft, the cylinder having an exhaust port, a pump operatively connected to the crank shaft, a pipe 105 establishing communication between the cylinder and pump, and a valve having a seat communicating with sources of air and water supply, said valve admitting air and water to said pipe during the suction stroke of the 110 pump, and said valve being arranged to close on the compression stroke of said pump whereby the mixed air and water is discharged into the cylinder to remove the consumed gases therefrom through its exhaust 115 port.

6. An internal combustion engine including a cylinder having a piston to operate therein and a suitable crank shaft, a pump, an inlet connected directly to the pump for 120 admitting a combustible mixture thereto, a pipe establishing communication between the pump and the engine cylinder, the latter being provided with an exhaust port, and a valve for simultaneously admitting air and 125 water to said pipe during the suction stroke of said pump, means for supplying a charge of combustible mixture also to the pump during its suction stroke, and means for operating said pump on its compression 130

stroke preliminarily to force the mixed air and water into the cylinder to discharge the consumed gases therefrom through its exhaust port, and subsequently for introducing 5 the combustible mixture into the engine cylinder.

7. An internal combustion engine including a set of three cylinders provided with suitable exhaust ports, pistons arranged to 10 operate in the respective cylinders, a crank shaft having cranks thereon set at equal angles about the shaft and connected to the respective pistons, a pump connected to operate with each piston, a pipe establishing 15 communication between each cylinder and one of said pumps, a valve mounted in each pipe for simultaneously admitting air and

water thereto during the suction stroke of its corresponding pump, and inlet valves to control communication between the cylinder and the respective pipes, said valves being arranged to open during the compression strokes of the respective pumps to admit mixed air and water into the corresponding cylinders to discharge the consumed gases 25 through the respective exhaust ports.

In testimony whereof I have hereunto set my hand in presence of two subscribing witnesses.
